UNITED STATES PATENT OFFICE

ALAN C. ARTHUR AND OTTO P. LAMPSON, OF VENTURA, CALIFORNIA

EXPANSION DRILL BIT

Application filed May 28, 1928. Serial No. 280,975.

Our invention relates to earth boring tools, and more particularly to rotary drill bits in which a set of pivoted cutter blades are adapted to be expanded to operative or cutting position, there being means associated with said bit whereby chattering of said blades is effectively prevented when said bit is being operated.

It accordingly is an object of our invention to provide a novel form of rotary bit in which a set of pivoted blades are so constructed as to provide a wedging action with the body portion of said bit when said blades are in expanded position, to prevent chattering thereof, means being also provided for effectively cooling said blades and sweeping away the cuttings formed by said blades, the cutting edge of at least one of said blades being extended inwardly to the center of said bit to cut the earth stratum in the center below said bit to avoid centering thereof.

It is also within the province of our invention to slightly incline the cutting edge of each blade from the outer to the inner edge for more effectively cutting the earth stratum, the cutting edge of said blades, if preferred, being of different lengths, and symmetrically positioned with respect to the bit.

The above and further objects and advantages of our invention, as will hereinafter more fully appear, we attain by the construction described in the specification, and illustrated on the drawings, forming a part of our application.

Reference is had to the accompanying drawings, in which similar reference characters denote similar parts. In the drawings,

Fig. 1 is an elevational view of our invention showing the pivoted cutter blades in expanded position,

Fig. 2 is a bottom plan view of Fig. 1,

Fig. 3 is a fragmentary elevational view showing the cutter blades in retracted position,

Fig. 4 is a fragmentary cross-sectional view illustrating the wedging or eccentric action of the blades in their sockets, and

Fig. 5 is a similar view taken at a right angle to Fig. 4.

Describing our invention more in detail,

the body portion 2 is preferably tapered as at 4 and has extended therefrom a shank 6, provided with a tapered extension 8 having threads 10 to which may be secured a means for rotating the bit.

The body portion 2 is cut away as at 12 to provide a set of sockets in which are positioned the cutter blades 14, preferably three in number, and pivoted in said sockets by any suitable means, such as the bolts 16, the body portion 2 being cut away as at 18 to accommodate said bolts or pivoting means, said body portion being also cut away as at 20 to provide for a ready disposal of the cuttings of the blades 14.

As seen in the drawings, the cutter blades 14 are of different widths, although said blades may be of the same width, if desired, and the cutting edge 22 of each of said blades is preferably slightly inclined from the outer edge thereof inwardly to the inner edge, as seen more particularly in Fig. 1, for the purpose of more effectively cutting the earth formation and to provide for even wear of the blades. It will also be observed that at least one of the blades 14 has its inner edge extending to the center of the bit for the purpose of cutting away the earth stratum at that point to avoid building up at the earth stratum and thus avoid centering of the bit so that a straight hole may be cut.

To provide a means for sweeping the cuttings from the bit and blades, and also to cool said blades, the bit is provided with a central circulating medium passage 24 connected with branch passages 26 leading to outlets 28 positioned forwardly of the blades 14. See Figs. 1 and 2.

When the bit 2 is inserted in the hole, the blades are in the position shown in Fig. 3, and when said blades are in operative position for drilling, they are expanded as disclosed in Figs. 1 and 2.

To prevent said blades from chattering while in expanded position, the sockets 12 are cut away on curved lines at their top portions both transversely as indicated at 30 (Fig. 5) and longitudinally as at 32 (Fig. 4), and the tops of each blade are also curved

as at 34, longitudinally, and transversely as at 36, but on different radii so that the tops of the blades will be eccentric with relation to the tops of the sockets. This will provide an increasingly wedging action as the blades 14 are expanded so that chattering will effectively be prevented in said position.

If desired, the blades 14 may be provided with a suitable means for limiting the extent 10 of their inward movement, such as the shoulders 38, which shoulders are adapted to engage the body 2 for this purpose. See Fig. 4.

While we have thus described our invention with great particularity, it will be clear 15 that the same may be modified throughout a wide range. We accordingly do not propose to be limited to the exact details of construction described and claimed, but reserve the right in practice to make any and all modifications thereof that fall within the scope of 20 the appended claims.

We claim as our invention:

1. A rotary drill bit including a threaded shank and a body portion, said body portion being provided with a set of independent sockets, said sockets being each curved at their top portions, and a cutter blade pivotally positioned in each of said sockets, each of said blades being curved at its top portion, 25 but on different radii than the curved parts of said sockets whereby a wedging action is had as said blades are expanded.

2. A rotary drill bit including a threaded shank and a body portion, said body portion being provided with a set of independent sockets having curved top portions, and a set 30 of cutter blades pivotally associated with said sockets, said blades being each cut-away at their top portions as well as their edges, 35 whereby a wedging action may be maintained between said blades and said sockets when said blades are expanded into cutting position.

3. A drill bit including a screw-threaded shank and a body portion, said body portion being provided with a set of independent sockets, a cutter blade pivotally positioned in each of said sockets, the top of each of 40 said blades being positioned in eccentric relation with the top of each of said sockets, whereby a wedging action may be had therebetween when said blades are expanded, and means associated with each of said blades 45 and said body portion for limiting the inward position of each of said blades.

4. A drill bit including a shank and a body portion, said body portion provided with a set of independent sockets and a cutting blade pivotally positioned in each of 50 said sockets, said blades having cutting edges of different lengths and slightly inclined from the outer edge to the inner edge, at least one of said blades extending inwardly 55 beyond the others to cut the formation in the center of the bit.

5. A drill bit including a shank and a body portion, said body portion being provided with a set of independent sockets, and a cutter blade, pivotally positioned in each of said sockets, the inner cutting edge of at 60 least one of said blades extending to the center of said body portion whereby the earth formation may be effectively cut in the center to avoid centering of said bit in said formation.

6. In a rotary drill bit, a body, means on said body whereby it may be attached to a string of pipe, said body being provided with cut-away portions for the disposal of the cuttings and a set of independent slots, a cutter blade in each of said slots, and pivotal means for each of said blades insertable through said blades in said cut away portions, said blades being adapted to be spread out from said body as said bit is operated, at least one of said blades extending inwardly beyond the others to cut the formation in the center of the bit.

7. A rotary drill bit comprising a body portion having a set of independent slots 70 extending in a substantially radial direction from the outer periphery of said body portion, and a cutter blade pivotally mounted in each of said slots, and in off-set relation therewith, the inner end of at least one of said blades extending inwardly a substantial distance beyond the inner ends of each of the other of said blades.

8. In a rotary drill bit, a body portion provided with a set of independent and spaced apart radial slots, an angular cutter blade each having a curved portion, pivotally mounted in each of said slots, each of said blades being adapted to have its angular portion spread from said body portion as said bit is operated, at least one of said blades extending beyond the others to cut the formation at the center of the bit.

9. A drill bit including a shank and a body portion cut away for the disposal of the cuttings, said body portion being provided with a set of independent and spaced apart radial slots, a combined curved and angular cutter blade pivotally mounted in each of said slots, said blades, when said bit is operated, being adapted to be spread out from said body portion, but when at rest being positioned substantially within the confines of said body portion, said cutter blades having cutting edges of unequal 100 length.

In testimony whereof we have signed our names to this specification.

ALAN C. ARTHUR.
OTTO P. LAMPSON.
